(57) **CLAIM**

The ornamental design for a wheel, as shown and described.

DESCRIPTION

FIG. 1 is a perspective view of a first embodiment of a wheel of Applicant's design; and

FIG. 2 is a front view thereof;

FIG. 3 is a perspective view of a second embodiment of a wheel of Applicant's design; and,

FIG. 4 is a front view thereof.

The broken lines shown in the drawings are included for the purpose of illustrating environmental structure and form no part of the claimed design.

1 Claim, 4 Drawing Sheets
